Primary Examiner — Katie Jane Stofko(74) Attorney, Agent, or Firm — Merchant & Gould P.C.(57) CLAIM

The ornamental design for a kabob pet treat, as shown and described.

DESCRIPTION

FIG. 1 is a front, bottom and right side perspective view of a kabob pet treat according to the new design;

FIG. 2 is a back, top, right side perspective view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a front elevation view thereof; and,

FIG. 8 is a back elevation view thereof.

The broken lines in FIGS. 1-8 illustrate portions of the kabob pet treat that form no part of the claimed design.
